(57) **CLAIM**

The ornamental design for a removable rail mount, as shown and described.

DESCRIPTION

FIG. 1 is a front top perspective view of a removable rail mount showing the new design;

FIG. 2 is a rear bottom perspective view;

FIG. 3 is a front elevational view;

FIG. 4 is a rear elevational view;

FIG. 5 is a side elevational view;

FIG. 6 is the opposite side elevational view, being a mirror image of the side shown in FIG. 5;

FIG. 7 is a top plan view; and,

FIG. 8 is a bottom plan view.

The broken lines depict portions of the “removable rail mount” that form no part of the claimed design.
